ICE BLOCK EJECTOR

Verlos G. Sharpe, Dayton, Ohio, assignor to General Motors Corporation, Detroit, Mich., a corporation of Delaware

Application February 14, 1957, Serial No. 640,170

2 Claims. (Cl. 62—344)

This invention relates to refrigeration and particularly to an improvement in devices for ejecting ice blocks from freezing devices.

With the advent and use of a single ice block ejecting device or element in a household refrigerator cabinet which is common to all the plurality of unitary freezing devices employed in the refrigerator and invertedly receives any selected one thereof for releasing ice blocks therefrom into a removable portable ice storage, dispensing, serving and harvesting receptacle or bucket of the type shown and described in my Patent No. 2,829,506 dated April 8, 1958 entitled Ice Block Harvesting Device and assigned to the assignee of the present application a problem has arisen. Such ice block ejecting devices are usually mounted or contained in the freezing or frozen food storage chamber of a refrigerator cabinet and frequently the portable ice block receiving and storage receptacle or bucket normally associated therewith is removed therefrom and left at the kitchen sink or on a dinner or cocktail serving table. When this occurs and another person wishes to harvest some ice blocks at the refrigerator he or she may fail to observe that the ice block storage receptacle or bucket is not in its proper or normal position within the freezing chamber and associated with the ice block ejecting device for receiving ice blocks. Thus this person will remove a unitary freezing device together with ice blocks frozen therein from the freezing chamber of the refrigerator and place same in inverted fashion upon the ice block ejecting device and operate the ice block ejecting mechanism thereof. Under such condition ice blocks will be ejected from the freezing device and will fall at random upon the bottom of the freezing chamber and be scattered throughout portions of the chamber and some of the ice blocks bounce or tumble out of the chamber onto the floor while its door is open during operation of the ice ejecting mechanism. This is very objectionable to users of refrigerators equipped with an ice block ejecting device or element of the character described and I contemplate the provision of means associated with an ice block ejecting device which will overcome such objection and eliminate or reduce to a minimum customer complaints.

An object of my invention is to provide an improved arrangement or device for ejecting ice blocks from a freezing device in a refrigerator cabinet into a portable ice block storage, dispensing and harvesting receptacle or bucket.

Another object of my invention is to provide means in an ice block ejecting device or apparatus which renders the ejecting mechanism thereof ineffective to eject ice blocks from a freezing device placed in supported relationship on the ejecting device automatically in response to removal of a portable ice block storage, dispensing and harvesting receptacle or bucket from association with the ice block ejecting device.

In carrying out the foregoing objects it is a further and more specific object of my invention to provide means in an operating mechanism of an ice block ejecting device

2

which prevents the mechanism from acting on a freezing device placed in an inverted supported position thereon and releasing ice blocks from the freezing device unless an ice block storing and harvesting receptacle or bucket is associated with the ice block ejecting device and located in a proper position therebelow to receive ice blocks to be ejected from the freezing device.

Further objects and advantages of the present invention will be apparent from the following description, reference being had to the accompanying drawings wherein a preferred form of the present invention is clearly shown.

In the drawings:

Figure 1 is a front view of a multiple chambered household refrigerator cabinet with the chamber doors shown open to illustrate the location of an ice ejecting device and ice block storage and harvesting receptacle of the present invention in the refrigerator cabinet;

Figure 2 is a broken enlarged fragmentary sectional view taken on the line 2—2 of Figure 1 and shows the mounting of the ice block ejecting device to walls of the freezing chamber of the refrigerator cabinet;

Figure 3 is a broken fragmentary sectional view taken on the line 3—3 of Figure 2 showing a unitary freezing device invertedly supported on a support of the ice block ejecting device with a part of a grid wall actuating member registering and being interlocked with a means of the ice block ejecting mechanism;

Figure 4 is a broken view similar to Figure 3 and shows a lever of the ice block ejecting mechanism on the ejector device moved into a position which breaks bonds between the grid and tray walls and ice blocks of the freezing device and ejects the ice blocks therefrom;

Figure 5 is a view similar to Figures 3 and 4 with the ice block storing and harvesting receptacle removed from the ice block ejecting device and rendering the ice block ejecting mechanism ineffective to eject ice blocks from a freezing device placed on the ejecting device;

Figure 6 is a fragmentary sectional view taken on the line 6—6 of Figure 3 showing a roller freezing device holding means on the ice block ejecting device; and

Figure 7 is a fragmentary sectional view taken on the line 7—7 of Figure 2 showing supports on the ice block ejecting device for supporting a freezing device and a portable ice block storing and harvesting receptacle thereon.

Referring to the drawings I show in Figure 1 thereof a refrigerating apparatus including an insulated household refrigerator cabinet 10 of the multiple chamber type in which the present invention is embodied. Cabinet 10 is provided with an upper unfrozen food storage chamber 11 which is cooled to a temperature of from, for example, 37° to 43° F., by a plate-like sheet metal evaporator 12 of a refrigerating system associated with the cabinet and located behind a protective cover or concealing baffle 13 both of which are secured to the back wall of chamber 11. Cabinet 10 is also provided with a lower or frozen food storage chamber 14 which is cooled to a temperature well below 32° F. for the storage of frozen foods, for freezing foods and/or for freezing water in freezing devices removably disposed in chamber 14 into ice blocks for table use in chilling drinks in glasses. Chamber 14 is refrigerated by an evaporator 15 of the refrigerating system associated with cabinet 10, which evaporator is in the form of a conduit coiled or wrapped around the outside of and suitably secured to a metal can-like member 16 forming the liner of chamber 14. An insulated door 17, shown in open position in Figure 1, is hingedly mounted on cabinet 10 at the front thereof to provide an individual closure for the access opening of chamber 11 and another insulated door 18, also shown in open position in Figure 1, provides an individual closure for the access opening of the freezing

chamber 14 as is conventional in the art. A resilient gasket 19 extends around each of the doors 17 and 18 for sealingly engaging the front of cabinet 10. A plurality of similar or identical unitary freezing devices, generally represented at 20, of the type including a tray and a grid locked therein against detachment therefrom may be supported, in an upright position, along the bottom wall of can-like member or liner 16 of chamber 14. The devices 20 are exposed to the low temperature of chamber 14 and are in metal-to-metal heat conducting relation with the evaporator 15 for freezing water contained in these devices into ice blocks or cubes. An ejecting device or element common to the plurality of freezing devices 20 and adapted to invertedly support and eject ice blocks from any selected one thereof is mounted in chamber 14 of cabinet 10, preferably at one side thereof.

Before proceeding further with the description of the present invention I wish it to be understood that each of the similar unitary freezing devices employed in conjunction with the use of the refrigerator 10 may be of the character shown and described in my patent hereinbefore referred to with minor changes incorporated therein having no bearing on the present invention. For the sake of brevity the specific construction of such a freezing device will not be herein described in detail since same may be varied without departing from the spirit of my invention as set forth by claims appended hereto. Epitomizing however each freezing device 20 includes a stamped sheet metal elongated tray 21 having a grid structure locked therein, in any suitable or desirable manner, against detachment therefrom to provide for movement of the grid walls and ejection of ice blocks while the freezing device is supported in an inverted position, as distinguished from conventional freezing devices wherein the grid structure in a tray is removable therefrom during the act of harvesting ice blocks. The grid structure comprises a metal longitudinal wall 22 having a plurality of spaced apart substantially inflexible or rigid metal walls 23 extending transversely across wall 22, to divide the interior of tray 21 into rows of ice block forming compartments, and a metal grid wall actuating member 24 substantially coextensive with wall 22 and located thereabove. The grid may be locked in tray 21 against removal or detachment therefrom in any suitable or desirable manner such, for example, as is described in my patent above identified. Rigid cross walls 23 are normally held in an inclined position with respect to the vertical and are adapted to be tilted toward the vertical, while the grid remains locked in tray 21, to effect ejection of ice blocks from the freezing device. Walls 23 and member 24 are all loosely anchored in tray 21 and interlocked together by webs and notches or the like in any conventional manner to permit shifting of member 24 lengthwise of longitudinal wall 22 to tilt cross walls 23 out of their angular or inclined position toward the vertical. Cross walls 23 are preferably tilted one after the other in succession progressively from end to end of device 20. This feature is old in the art and is disclosed in the Donald H. Reeves Patent No. 2,219,079, dated October 22, 1940 and greatly contributes to the successful operation of tilting inclined grid walls in a tray while a grid remains locked therein. The grid wall tilting or actuating member 24 is provided with a part or cut out notch, indicated at 26, which is adapted to register and interlock with a means forming a portion of a force multiplying manually operated leverage mechanism of an ice block ejecting device or element, to be presently described, when the freezing device together with the grid and ice blocks therein are inverted and has the top rim 27 on tray 21 supported upon same.

The single or common ice block ejecting device within compartment 14 of the refrigerator cabinet 10 includes a supporting element for receiving and supporting, in inverted fashion, a freezing device 20. The ice block

ejecting device or element includes a substantially inverted L-shaped sheet metal shell 31 provided with a vertical extension 32 and a horizontal foot 33 which are secured, by suitable bolts or the like 34, to an upright wall and to the bottom respectively of liner 16 of compartment 14. This shell 31 forms a compartment within chamber 14 at one corner thereof (see Figure 1) wherein ice blocks can be removed from a freezing device 20 and stored in dry form until removed from the refrigerator cabinet 10. Opposed rails 36, preferably of molded plastic material, are stationarily mounted, by screws or the like 37, on the shell extension 32 and the vertical leg of shell 31 respectively (see Figure 2). Each rail 36 is provided with vertically spaced apart shoulders or inwardly directed projections forming an upright track or support 38 and a lower track or support 39 (see Figures 3, 4 and 5). The upper track 38 is adapted to receive and support one of the unitary freezing devices 20 and lower track 39 removably receives and suspendingly supports an elongated ice block storage and harvesting receptacle or bucket 41 from an integral raised top rim 42 provided on the receptacle or bucket. Receptacle or bucket 41 is preferably formed of molded plastic material and has a handle 43 at one or the front end thereof. A reinforcing metal bracket 44 extends across the back of shell 31 and is riveted or otherwise suitably secured thereto for abutment by the rim 27 on the back end of tray 21 of a freezing device 20. The ice block ejecting element or device includes a manually operated force multiplying leverage mechanism which comprises a bail-like lever having arms 46 connected together, in any suitable manner, at one end thereof such as by a molded plastic handle 47. The other end of arms 46 of the bail-like lever are attached to shell 31 as by round shafts or pins 48 so as to be pivotally movable or swingable in a vertical direction relative to the shell or to the ice block ejecting element or device. Opposed studs 49 riveted to the shell extension 32 and to the upright leg of shell 31 respectively each carry a collar-like roller 51. The rollers 51 serve a dual purpose in the present disclosure in that the rim 27 on tray 21 of a freezing device 20 can be freely moved therealong with respect thereto and that they form stops or abutments for holding a freezing device 20 stationary on the ejecting device. The mounting of shafts or pins 48 and studs 49 are reinforced by being extended through substantially triangularly shaped metal pieces 52 secured to opposed sides of shell 31 by rivets 53. A portion of each of the arms 46 of the bail-like lever close to the pivot 48 of ends thereof has a pin or stud 54 secured or riveted thereto. These pins or studs 54 pivotally carry ends 56 of a substantially U-shaped metal means or yoke 57. Yoke means 57 is provided with extensions 58 at each side thereof which, in accordance with my invention, lie over and normally engage or rest on the top rim 42 provided on receptacle or bucket 41 suspended from the lower set of supports or tracks 39. These extensions 58 on yoke 57 are also adapted to engage and rest on supports 39 in a manner and for a purpose to be hereinafter described when receptacle 41 is slid out of the ice block ejecting device and removed from chamber 14. The base or that part of yoke or means 57 connecting the ends or legs 56 thereof is bent into a substantially channel shape in cross section as shown so as to provide the same with a reinforced portion which is normally held in a predetermined elevated position by the rim 42 on receptacle 41 so as to register and interlock with the part or notch 26 of a grid wall actuating member 24 of a freezing device 20 when the freezing device is invertedly supported on the supports 38 of the ice block ejecting device or element.

Having described the construction of the improved ice block ejecting element or device I will proceed to describe the operation thereof in order to set forth the feature of my invention incorporated therein. Assume

that water has been hard-frozen into separated ice blocks in the upright freezing device 20 within chamber 14 of the refrigerator cabinet 10 and it is now desired to harvest ice blocks from a selected one of the unitary freezing devices 20. Assume also that the portable ice storage receptacle or bucket 41 is in its proper place on supports 39 within the shell 31 of the ice block ejecting device as shown in Figure 3 of the drawings. The selected freezing device 20 is removed from the freezing chamber 14 and together with the grid locked in tray 21 and ice blocks therein is rotated as a unit into an inverted position and inserted in the ice block ejecting element or device. The rim 27 on tray 21 of the inverted freezing device 20 engages and rotates the rollers 51 as the device 20 is slid into the ejecting device. When the front end of freezing device 20 passes inwardly beyond rollers 51 the device 20 will drop upon the opposed tracks or supports 38 with the front of tray 21 thereof adapted to abut against these rollers which form stops to hold the device 20 stationary relative to the ice block ejecting device. The handle on the front end of freezing device 20 is cut away or shaped to clear or miss the rollers 51 upon inserting device 20 into the ice block ejecting device. As the rim 27 on tray 21 of the freezing device 20 comes to rest on supports 38 that part of or notch 26 in grid wall actuating member 24 registers and interlocks with the yoke means 57 since this yoke means is held in a predetermined elevated position by its side extensions 58 bearing against the rim 42 on ice storage receptacle 41. Notch 26 receives the channel shaped base part of yoke 57 by its walls straddling same (see Figure 3). The handle 47 of the ice block ejecting lever may now be raised or swung upwardly about its pivotal mounting points or pins 48. This upward swinging of the lever of the ejecting mechanism causes same to pull yoke means 57 forwardly, relative to the ice block ejecting device and freezing device 20 supported thereon, whereupon its engages a side wall of notch 26 on member 24 and shifts the actuating member lengthwise along grid wall 22 with respect to tray 21 of the invertedly supported freezing device. Tray 21 abuts the stops or rollers 51 at this time to prevent lengthwise movement of freezing device 20 relative to the ice block ejecting device, and since the force exerted by yoke 57 on member 24 is in a horizontal direction the freezing device does not rise off the supports 38. Shifting of grid wall actuating member 24 in this manner causes a wall of the spaced apart notches in this member to engage and tilt the grid cross walls 23, preferably one after the other in succession progressively from end to end of the freezing device, toward or beyond a vertical plane to eject ice blocks from device 20 downwardly out of their compartments into the ice storage and harvesting receptacle or bucket 41 (see Figure 4). Thereafter the swingable lever of the mechanism is returned to its normal or lowered position as shown in Figure 2 and the unitary freezing device from which the ice blocks have been ejected may be removed from the ice block ejecting device or element, refilled with water and repositioned within chamber 14 of cabinet 10 to freeze the water into another batch of ice blocks. The portable storage receptacle or bucket 41 can be slid to and fro on its supports 39 intermediate arms 46 of the lever with respect to the ice ejecting device in chamber 14 to provide access to and harvesting of the ice blocks therein or it can be bodily removed therefrom and from cabinet 10 and carried to a dinner or cocktail serving table. It is to be noted that when receptacle 41 is removed from its supports 39 on the ice ejecting device and from cabinet 10 the yoke means 57 swings down by gravity around its pivotal mountings, pins or shafts 54, and the side extensions 58 thereon come to rest on the supports 39 (see Figure 5). This positions the channel shaped portion of yoke 57 below its normal position at which the same is held elevated by the thick rim 42 on receptacle 41. It should be observed,

by reference to the showing by dot-dash lines in Figure 5 of the drawings of a fragmentary part of a freezing device 20 supported on the ice block ejecting device, that yoke means 57 cannot now fit in or interlock with notch 26 of an actuating member 24 of one of the similar freezing devices 20 upon placing same in supported position on the ice block ejecting device. Thus the feature of my invention has come into play since the yoke means of the ice ejecting mechanism, which ordinarily registers and interlocks with a part, notch 26, of a grid wall actuating member 24 of a freezing device 20, has now been rendered ineffective automatically in response to removing the receptacle 41 from the ice block ejecting device. Therefore if the lever of the mechanism is operated after a person invertedly supports another freezing device 20 on the ejecting device, while receptacle 41 is removed therefrom and remains out of association therewith at a place remote from cabinet 10, no ice blocks can be ejected from this another freezing device until the storage and harvesting receptacle or bucket 41 is repositioned on its supports 39 of the ice block ejecting or releasing device. In this manner I overcome a troublesome problem which has developed in the use of devices of the type herein disclosed and provide a practical apparatus of increased utility. It is believed to be obvious to one skilled in the art since the side extensions 58 of yoke 57 rest on supports 39, when ice block storage receptacle 41 is removed from its supports, that these extensions are in the path of movement of this receptacle when it is replaced or slid onto the supports 39 and that such replacement will raise the channel shaped base portion of yoke 57 from the position thereof shown in Figure 5 to its normal elevated position as shown in Figure 3. This thereby again renders the ice ejecting mechanism of the ice ejecting device effective whereby the yoke 57 can register and interlock with an actuating member 24 of a freezing device 20 to be placed on the upper supports 38 of the ejecting device.

From the foregoing it should be apparent that I have by rendering an ice block ejecting device ineffective, upon removing an ice storage and harvesting receptacle or bucket therefrom, to eject ice blocks from a freezing device invertedly placed into association with the ejecting device provided an improved apparatus and that my improved apparatus overcomes a problem which has created customer objections. My invention provides for the control of ejected ice blocks from a unitary freezing device in a manner whereby the ice blocks are at all times collected as a group in an ice block storing and harvesting receptacle or bucket to thereby avoid scattering the ice blocks throughout a freezing compartment of a refrigerator cabinet in which they are to be maintained in dry form and whereby ejected ice blocks can not tumble or be tossed out of such compartment while its door is open during the act of operating an ice block ejecting device. The feature of the present invention can be incorporated in an ice block ejecting device without adding to the cost of manufacturing such device and is a desired, novel and practical improvement.

While the form of embodiment of the invention as herein disclosed constitutes a preferred form, it is to be understood that other forms might be adopted, as may come within the scope of the claims which follow.

What is claimed is as follows:

1. In combination, a freezing device receiving element having an open bottom support thereon, a freezing device containing a plurality of ice blocks bonded therein placeable in an inverted supported position on the support of said element, a stop cooperating with the support on said element holding the invertedly supported freezing device stationary thereon, a portable ice storage and dispensing receptacle removably located below the open bottom support on said element in vertical alignment therewith, a force multiplying mechanism movably mounted on said element including a rigid means pivoted

thereon shiftable therewith and relative thereto, said rigid means having a part thereof normally abutting said removable receptacle and held thereby for engagement with a portion of said freezing device upon operating said mechanism to break bonds between ice blocks and the freezing device while same is stationarily supported on said element and to mechanically eject all of the ice blocks from the device whereby they fall through said open bottom support directly into the receptacle aligned therewith, said part of said rigid means being shifted automatically in response to removing said receptacle from said element into a predetermined position thereon with respect to said mechanism, said mechanism being operable irrespective of the location of said receptacle and during its removal from said element to move said rigid means therewith, and the shifting of said part of said rigid means into said predetermined position thereof rendering same ineffective by operation of said mechanism to eject ice blocks from a freezing device placed on said support element subsequent to removal of the receptacle therefrom.

2. In combination, a freezing device receiving element having an open bottom support thereon, a freezing device containing a plurality of ice blocks bonded therein placeable in an inverted supported position on the support of said element, a stop cooperating with the support on said element holding the invertedly supported freezing device stationary thereon, a portable ice storage and dispensing receptacle removably located below the open bottom support on said element in vertical alignment therewith, a force multiplying mechanism movably mounted on said element including a rigid means pivoted thereon shiftable therewith and relative thereto, said rigid means having a part thereof normally resting on an upper edge of said removable receptacle and held thereby in a

position between said freezing device and the receptacle for engagement with a portion of the device, operation of said mechanism moving said part of said rigid means along said upper edge of said receptacle while engaging 5 said portion of said freezing device stationarily supported on the support of said element to break bonds between ice blocks and the device and to mechanically eject all of the ice blocks therefrom whereby they fall through said open bottom support directly into the receptacle aligned therewith, said part of said rigid means being shifted automatically in response to removing said receptacle from said element off the receptacle upper edge into a predetermined position on the element with respect to said mechanism, said mechanism being operable irrespective of the location of said receptacle so as to be operated 10 while the receptacle is removed from said element to move said rigid means, and the shifting of said part of said rigid means off the edge of said receptacle into said predetermined position thereof rendering same ineffective by operation of said mechanism to eject ice blocks from a freezing device placed on said support element subsequent to removal of the receptacle therefrom.
